UNITED STATES PATENT OFFICE.

MAX RACHLIN, OF BROOKLYN, NEW YORK.

EAVES-TROUGH ELBOW.

Application filed November 12, 1926. Serial No. 147,962.

The present invention relates to improvements in elbows, that is to say to a short fitting of the type which is employed to make a joint between two eaves-trough sections at 5 an angle to each other.

One of the difficulties with which the tinsmith meets in joining sections of eaves-troughs at an angle consists in that the elbows heretofore in use are not adjustable and 10 are thus not adaptable to the slight variations of the angles between the projecting edges of a roof. If for instance the angle between the eaves is somewhat smaller or larger than 90° , a 90° elbow will obviously not serve 15 its purpose without changing the relation between its two sections. Heretofore it has been a common practice to adapt the elbow to the variations in the angle between the eaves-trough sections by cutting the elbow 20 partly on the line bisecting the angle and then bending the two elbow sections toward and away from one another, as necessary, and finally soldering an insert to the elbows at the cut between the two sections. The operations outlined require time and labor and 25 can be performed by skilled mechanics only.

The main object of the present invention is to provide an elbow of the type mentioned which is expansible and contractible on a 30 line bisecting the angle between its sections, thereby overcoming the difficulties above referred to.

A further object of the invention is to provide an elbow of the character mentioned 35 which is made of one integral piece, preferably by stamping operations, and which is simple in construction and capable of manufacture on a commercial scale, or in other words one which is not so difficult to make as 40 to be beyond the reasonable cost of such a contrivance.

With these and other objects in view, which will more fully appear as the nature of the invention is better understood, the 45 same consists in the combination, arrangement and construction of parts hereinafter described, pointed out in the appended claims and illustrated in the accompanying drawings, it being understood that many changes 50 may be made in the size and proportion of the several parts and details of construction within the scope of the appended claims, without departing from the spirit or sacrificing any of the advantages of the invention. 55

One of the many possible embodiments of

the invention is illustrated in the accompanying drawings, in which:

Figure 1 is a top plan view of an elbow constructed in accordance with the present 60 invention; Fig. 2 is a side elevation thereof; Fig. 3 is a section taken on line 3—3 of Fig. 1, on a larger scale; Fig. 4 is a section taken on line 4—4 of Fig. 1; Fig. 5 is a section taken on line 5—5 of Fig. 1; and Fig. 6 is a 65 plan view of the blank of which the elbow is formed, the said blank being shown on a somewhat reduced scale.

Eaves-troughs, as commonly employed in the present day practice, are usually provided with a bead at their outer edge, while their inner edge is plain. Consequently the elbow used for joining the same at an angle must be provided with a bead at its outer edges, while the inner edges must be plain. 70 The elbow forming the subject matter of the present application for Letters Patent is made from a sheet metal blank 10, shown in Fig. 6 of the drawings, shaped by stamping operations. This blank comprises two 75 sections 11 and 12 meeting at an angle at the dotted line 13 shown in Fig. 6, said line bisecting the angle between the said two sections and also bisecting a substantially circular projection 14, which joins the outer 80 longitudinal edges 15 of the blank. This blank is shaped by dies into the form of an elbow, as shown in Fig. 1 of the drawings, the said elbow comprising two short sections 16 and 17, each trough shaped and 85 meeting along the bisecting line 13 at right angles to one another, although this is not essential, it being obvious that any suitable angle may be employed according to the requirements. Those portions of the blank 90 which are adjacent the outer edges 15 are shaped to form beads 18, while the opposite edges of the blank are left plain, as clearly 95 shown in Fig. 4 of the drawings. The substantially circular projection 14 of the blank 100 is formed into a spherical body 19, onto which the adjacent portions of the beads are 105 bent, as shown at 20. The portions 20 fit closely the spherical body, for the purpose hereinafter to be described.

In parallel relation and adjacent to the line 13 are formed the elbow corrugations 21, which extend from the plain edges of the elbow a substantial distance toward the intersecting longitudinal axes of the two sections of the elbow. From the juncture of the two beads of the elbow extends toward 110

the two axes mentioned along the line 13 a depression 22, the purpose of which is to strengthen the construction and also to take care of the excess material at this region.

5 In use, if it is found that the angle between the two sections of the elbow is either too large or too small, the working man takes hold of the elbow at the plain edges thereof and either forces them toward one another or away from one another, as it may be required, the corrugations 21 permitting of a shaping of the elbow. As the plain edges of the elbow are forced in one or the other direction, the portions 20 of the beads 10 move upon the spherical body 19 accordingly, the said last-named portions being loose, that is to say unattached to the spherical body. It will thus be seen that the angle between the two sections of the elbow can be 15 conveniently changed without the aid of tools and without the elbow being deformed in a way that its appearance would be impaired.

What I claim is:

1. A one piece elbow of the character described comprising two trough shaped sections meeting at an angle, each section having a plain inner edge and a beaded outer edge, a spherical body at the juncture of and projecting beyond said beads, a portion of each bead overlying said spherical body and having an inner surface conforming to the outer surface of said spherical body, and corrugations on said elbow sections extending from the plain edges thereof toward said spherical body in parallel relation to the line bisecting the angle between said elbow sections. 25

2. An elbow according to claim 1, having a depression formed therein extending from the junction of said two beaded outer edges along said bisecting line toward the junction of the plain edges thereof. 30

Signed at New York, in the county of New York, and State of New York, this 9th day 35 of November, A. D. 1926.

MAX RACHLIN.
